[57] CLAIM

The ornamental design for a pocket insert for a notebook, as shown and described.

DESCRIPTION

FIG. 1 is a front elevational view of a pocket insert for a notebook showing my new design;
FIG. 2 is a rear elevational view thereof;
FIG. 3 is a front perspective view thereof;
FIG. 4 is an end elevational view thereof with the pockets in a slightly flexed condition;
FIG. 5 is a front elevational view of a developed plan view of the pocket insert for a notebook; and
FIG. 6 is a rear elevational view thereof.
